United States Patent Office

Des. 176,440
Patented Dec. 27, 1955

176,440

BOTTLE

Jack Bloch, Leominster, Mass., assignor to Foster Grant Co. Inc., Leominster, Mass., a corporation of Massachusetts

Application May 16, 1955, Serial No. 35,987

Term of patent 14 years

(Cl. D58—8)

FIG. 1.

FIG. 4.

FIG. 2.

FIG. 5.

FIG. 3.

Fig. 1 is a side elevation view of a bottle showing my new design;

Fig. 2 is a top plan view thereof;

Fig. 3 is a bottom plan view thereof;

Fig. 4 is a rear end elevation view thereof; and

Fig. 5 is a fragmentary view of the top portion of the bottle, taken partly in cross-section and partly in full elevation.

I claim:

The ornamental design for a bottle, substantially as shown.
